UNITED STATES PATENT OFFICE

2,410,627

TOY

Arthur Brand, New York, N. Y.

Application April 22, 1944, Serial No. 532,316

3 Claims. (Cl. 46—74)

1

This invention relates to toys. It is particularly directed to an air-glider type toy which a child may throw in the air and which will glide through the air for a comparatively considerable distance.

An object of this invention is to provide a toy of the character described which can be made of two parts, either stapled or otherwise attached together, and which can be manufactured at very low cost.

Another object of this invention is to provide a toy of the character described which can be made to resemble various birds, such as canary, pigeon, robin, swallow, or blue jay, or other birds or objects.

Yet another object of this invention is to provide a toy of the character described which may be made from a single sheet of paper and a piece of wood such as pine or balsa or other similar material attached to the sheet of paper.

Still another object of this invention is to provide a toy of the character described so proportioned that the toy will carry for long distances when thrown into the air even by a child.

Still a further object of this invention is to provide a simple, compact and durable toy of the character described which shall be relatively inexpensive to manufacture, easy to ship, and which shall yet be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing in which is shown one of the various possible illustrative embodiments of this invention,

Fig. 1 is a side elevational view of a toy embodying the invention;

Fig. 2 is a top plan view thereof; and

Fig. 3 is a front elevational view of the toy.

Referring now in detail to the drawing, 10 designates an air-glider toy embodying the invention. The same comprises a body 11 which may be made of paper, cardboard, or the like flexible or semi-stiff sheet material. The body 11 comprises a pair of similar folded back portions 12 folded along a bottom crease line or fold line 13. Extending from portions 12 are combination wing and tail portions 14. Each of the portions 14 comprises a front wing portion 15 and a

2

rear tail portion 16 extending therefrom. The portions 14 comprise sections 17 extending from portions 12 and being inclined upwardly and outwardly as shown in Fig. 3 of the drawing. The tail portions 16 are integral with sections 17. Between portions 12 and sections 17 are crease lines 18.

Extending from said sections 17 are sections 19 connected to sections 17 by crease lines 20 parallel to the crease lines 18. Extending from sections 19 and inclined downwardly and outwardly are sections 25 connected to sections 19 by crease lines 26. Crease lines 26, 20 and 18 are horizontal.

15 The tail 16 is about one-fifth to one-third the length of the body 11.

Interposed between portions 12 of the body 11 is a vertical flat piece 30 of wood or other similar material such as pine or balsa wood, stapled to portions 12 of the body 11 by means of a staple 31. Member 30 is made of material stiffer and preferably thicker than the material of which member 11 is made. The rear ends of portions 12 of the body are stapled together by a staple 32 located adjacent the rear end of the body. The staples 31, 32 are aligned with one another, in a horizontal position extending longitudinally of the toy. It will be noted that the body is shaped to resemble the wings and tail of a bird. Member 30 may be shaped to simulate the head and body of a bird. Thus member 30 has a rear body portion 33 and a front head portion 34. The head portion 34 projects forwardly of the body 11. The upper portion of the body 33 projects above portions 12 of the body 11.

35 Preferably the center of gravity of the toy is one-quarter to one-third the distance from the forward edge of body 11 to the rear end thereof.

It has been found that the crease lines 18, 20 and 26 give the wings a certain amount of flexibility which permits the toy to travel considerable distance when thrown forwardly. The child holds the bottom of the toy between his fingers and throws the toy forwardly. The toy 40 may be shipped flat by folding the wings 14 into contact with one another and the child may fold the wings into desired position along the fold lines 18, 20, and 26 after the toy is purchased.

Although the toy is shown to resemble a bird, 45 it will be understood that the toy may represent a glider, airplane, or any other object.

It will be noted that the toy comprises the parts 30 and 11 stapled together by an ordinary paper staple. Of course these two parts may be assembled together by glue if desired. The staples

31 are preferably located adjacent the fold line 18, that is, close to the upper edge of portions 12 of the body 11. The body 33 of member 30 preferably substantially fits down to the fold line 13 and affords a good finger grasp for the child when propelling the toy forwardly.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A toy of the character described comprising a member made of sheet material having folded together portions, a second member between said folded together portions and attached thereto, said first member having wing portions and a tail portion, said second member extending above the folded together portions and having a portion extending forwardly of said first member, said

wing portions having a plurality of parallel crease lines and comprising downwardly and outwardly inclined sections.

2. A toy glider comprising a member made of flexible sheet material having portions folded against one another, a relatively stiff sheet member between said folded together portions, means to attach the stiff member to the first member, said first member having diverging portions extending upwardly and outwardly from the folded back portions and portions inclined downwardly and outwardly, extending from said diverging portions.

3. A toy glider comprising a member made of flexible sheet material having portions folded against one another, a relatively stiff sheet member between said folded together portions, means to attach the stiff member to the first member, said first member having portions extending outwardly from the folded portions, said stiff member having a portion extending above said folded together portions, and a portion extending forwardly of said folded portions, said outwardly extending portions having upwardly and outwardly diverging parts and downwardly and outwardly inclined ends.

ARTHUR BRAND.
